(57) **CLAIM**

The ornamental design for a sombrero juicer as shown and described.

DESCRIPTION

FIG. 1 is a front, right-side and top perspective view of a sombrero juicer showing our new design;

FIG. 2 is a front, left-side and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross-sectional view thereof taken in the direction of line 9-9 in FIG. 7.

The dot-dash broken line in FIG. 7 shows the cross sectional line for FIG. 9 and forms no part of the claimed design.
